TYPEWRITING AND LIKE MACHINES

Elbert S. Dodge, Ilion, N. Y., assignor to Remington Rand Inc., Buffalo, N. Y., a corporation of Delaware

Application October 9, 1936, Serial No. 104,745

15 Claims. (Cl. 197—70)

My invention relates to typewriting and like machines and more particularly to tabulating mechanism therefor.

The main object of my invention, generally stated, is to provide a simple inexpensive and easily manufactured column stop mechanism for use in typewriting, computing and like machines, and which is highly efficient in use and which may be combined with existing tabulator mechanism of such machines without modifying, or materially modifying, the existing structural features thereof.

A more specific object of my invention is to provide in a mechanism of the character specified an improved column stop which may be constructed of a single integral piece of metal, and which is combined with and adapted for mounting on a special column stop bar construction for movement thereon into either a projected or retracted position and to be arrested in and held against accidental displacement from either said projected or said retracted position by an improved detent means.

To the above and other ends which will hereinafter appear, my invention consists in the features of construction arrangements of parts and combinations of devices set forth in the following description and particularly pointed out in the appended claims.

In the accompanying drawings, wherein like reference characters designate corresponding parts in the different views:—

Fig. 1 is a fragmentary, vertical fore and aft sectional view through the upper rear portion of a typewriting machine in which the devices of my invention have been embodied.

Fig. 2 is an enlarged, detail, top plan view of a portion of the column stop assembly shown in Fig. 1.

Fig. 3 is a detail, perspective view of the portion of the column stop assembly shown in Fig. 2.

Fig. 4 is an enlarged, detail, perspective view of a member of the column stop assembly.

Fig. 5 is an enlarged perspective view of the column stop assembly with the column stops removed and the detent bar shown separated from its actual position relative to the column stop bar.

Fig. 6 is an enlarged, detail, fragmentary front elevational view of a portion of the column stop assembly taken along line 6—6 of Fig. 1 and viewed in the direction of the arrows at said line.

Fig. 7 is an enlarged, detail, vertical sectional view taken through the column stop bar along line 7—7 of Fig. 2 and showing particularly the

first of the column stops in a retracted position and the next column stop in the projected position.

Fig. 8 is a like view of the same taken along line 8—8 of Fig. 2 and showing particularly the first column stop in the projected position and the next column stop in the retracted position.

I have shown my invention, in the present instance, embodied in a standard Remington typewriting machine in which the invention may be readily incorporated without modifying, or materially modifying, the existing structural features of the machine. Only a sufficient number of parts of the machine have been shown to illustrate the invention in its embodiment therein. It is to be understood, however, that the present invention is not restricted to embodiment in said machines, but may be applied to typewriting, accounting and like machines generally, wherever found available.

The usual top plate 10 of the machine is shown with a carriage supporting rail 11 suitably fixed thereto. The carriage which is of the usual construction and is conventionally shown in part carries a platen, diagrammatically indicated at 12, and comprises end bars 13 and a rear cross bar 14 grooved in its rear side. A similar groove is provided in the front side of the rail 11 so that said grooves or raceways jointly receive crossed anti-friction rollers 15. These rollers 15, together with corresponding means (not shown) at the front of the machine, support the carriage for movement over the top plate 10 from side to side of the machine, under propulsion in the direction of its feed of the usual spring drum, which has also been omitted from the present drawings.

A feed rack supporting frame 16 pivotally mounted at 17 to the rear cross bar 14 of the carriage supports a feed rack 18 which normally meshes with a feed pinion 19 carried by an escapement shaft 20. The rear end of the shaft 20 carries an escapement wheel coacting with feed dogs, all of which has been omitted from the present drawings and will be considered to be of the usual construction affording a definite character spacing movement of the carriage upon the operation of a printing key or the space bar. The feed rack frame 16 may receive an upward pivotal motion about its pivots 17 by the actuation of any of the usual tabulator keys, through the usual means, which have not been shown, to lift the feed rack 18 from engagement with the pinion 19 and free the carriage from control of its escapement mechanism.

The column stop assembly of the present in-

55

vention will later be described in detail, but in generally describing its embodiment in the machine illustrated in Fig. 1, it may be considered briefly as including a column stop bar designated 5 as a whole by the reference numeral 25 which extends throughout, or substantially throughout, the length of the carriage. This bar carries column stops, each designated as a whole by the reference numeral 30, which column stops, in the 10 present instance, are intended to be spaced at letter-space distances apart along the stop bar 25, so that each position at which the carriage may be arrested by the escapement mechanism brings one of said stops into alignment with key 15 controlled stop setting means to be hereinafter referred to. The column stops 30 normally assume a forward or ineffective position on the stop bar 25 but are slideable transversely thereof to a rearward or effective position by any suitable 20 means, such for example as the key-actuated setting means shown in Fig. 1.

The key-actuated setting means for the column stops partially illustrated in Fig. 1 is of the usual construction comprising a vertically extending setting arm 40 pivotally carried at 41 by a bracket 42 suitably mounted on the top plate 10 of the machine frame, and movable rearwardly through an actuating arm 43 connected at 44 to a depending link 45 actuated by 25 a key in the keyboard of the machine in the usual manner. The arrangement of this setting means is such that when the setting key is depressed, one of the column stops 30 which, according to the position of the carriage, is opposite or in line with the upper end of the setting lever 40 is moved rearwardly on the stop bar 25 from its normal position to a projected or effective 30 position.

When a column stop 30 is in its projected or 40 effective position, it is adapted to coact with one of the usual denominational stops which is projected to effective position or with any other tabulator means with which the column stops are intended to coact. In the present instance, one 45 of the denominational stops is shown at 50 as pivoted at 51 to the usual tabulator frame 52 secured at the rear of the frame of the machine. Each denominational stop 50 is controlled from a tabulator key (not shown) in the keyboard of 50 the machine, and a depression of a tabulator key moves the upper end of the corresponding denominational stop 50 forwardly into the path of the projected column stop or stops 30 and also (by means not shown) disengages the feed rack 55 55 18 from the escapement pinion 19, whereby the carriage moves freely in the direction of its feed until the first projected column stop 30 engages the actuated denominational stop 50.

When the depressed tabulator key is released, 60 the actuated denominational stop returns to its normal rearward position and the carriage rack re-engages with the escapement pinion to restore the control of the carriage to the escapement mechanism.

65 The column stops 30 may be restored from a projected position to a normal or retracted position by any suitable means which has herein been shown as the usual wiping plunger 55 housed in the tabulator frame 52. Said plunger 70 is manually shifted in a forward direction by a finger piece 56 against the force of an expansion spring 57 to move a cam-shaped wiper head 58 into the path of projected column stops. A movement of the carriage then causes the wiper head 58 to cam any projected column stop 30

forwardly to a retracted normal position on the column stop bar 25 in the usual manner.

Having thus generally described, in connection with Fig. 1 of the accompanying drawings, the arrangement and operation of one form of a complete tabulator stop mechanism, I shall now describe in detail the improved column stop assembly provided by the present invention. In other words, my invention is concerned chiefly with that portion of the complete tabulator 10 mechanism which usually is mounted on the carriage of the machine, and accordingly its embodiment in the machine shown and described above in connection with Fig. 1 has been given merely to illustrate the use of the devices of my 15 invention in machines in general and obviously may be embodied in other machines wherever found available.

The column stop bar 25 of the present column stop assembly may be of a construction very similar to that ordinarily used in Remington machines and may be mounted on the carriage in a like manner. Thus the bar 25 is shown in Fig. 1 as mounted at the rear ends 26^a of two end supporting brackets 26 extending upwardly and 25 rearwardly from the carriage cross bar 14. The stop bar 25 is retained on the ends of the brackets 26 by headed screws 27 (see Fig. 3) threaded into tapped holes 28 in opposite ends of the stop bar 25. Said stop bar 25 is shown in the present 30 instance as substantially square in cross section and the portion intermediate its ends is provided with oppositely disposed teeth 25^a between which transverse slots, notches or interdental spaces 29 are provided, which slotted or toothed sides, as they are shown in Fig. 1, are the upper and lower sides of the bar. The slots 29 are in transverse alignment and are spaced at letter-space intervals, which may be ten or twelve to the inch, for example, depending on whether the 40 machine is provided with pica or elite type, or are otherwise spaced according to the letter spacing of the carriage.

The column stops 30 are thin blade-like members stamped or punched from sheet metal of a thickness fitting snugly within the slots 29 of the stop bar 25 and affording nevertheless a free sliding movement of the stops in said slots into and out of effective position. A slot or bifurcation 31 is provided in each of the column stops 30 and is of sufficient width to receive and enable stops to slide on the body portion 25^b of the stop bar 25 which lies between the oppositely disposed toothed portions thereof, each slot 31 being of sufficient length to allow the required movement of the column stops 30 between their normal and projected positions. In this manner the column stops 30 are guided for movement transversely of the stop bar 25 by the interfitting arrangement of those parts of each stop on opposite sides of its slot 31 with the walls of the oppositely disposed slots 29 of the stop bar 25.

A means for arresting and holding the column stops 30 in their retracted or projected positions and for ordinarily preventing removal of the column stops from the stop bar 25 is provided in accordance with the present invention by an integral yieldable detent portion 32 of each of the column stops 30 which coacts with a relatively fixed retaining bar 33. The yieldable portion 32 of each of the column stops is in the same plane as the body portion and is formed by a slot 34 the walls of which extend parallel with and beneath the walls of the guide slot 31. The width of the central portion of the slot 34 is sufficient 75

to receive the body portion of the retaining bar 33 and afford a sliding movement of the stop thereon. However, the front end of the slot 34 is of a reduced width forming a stop lug 35 engageable with the front edge of the retaining bar 33 and thereby preventing an accidental detachment of each stop from the stop bar 25.

The retaining bar 33 is separate and distinct from the column stop bar 25 but extends beneath and parallel with the same throughout at least the portion of the stop bar between the ends 26^a of the brackets 26. The retaining bar 33 is held in such position against vertical displacement by the interlocking action of the column stops 30 which partially embrace both the stop bar 25 and the retaining bar 33. In order to hold the retaining bar 33 against horizontal fore and aft displacement relative to the stop bar 25, a key member 36 having T-shaped ends 36^a, 36^b (see Fig. 4) is provided preferably at the central and end portions of the retaining bar 33. The stem or central body portion of each of the key members 36 extends between hand contacts with the crown of one of the lower teeth 25^a of the stop bar 25 and the upper surface of the retaining bar 33 and is located in each instance in the space between the two adjacent column stops 30. The central body portion of each of these key members 36 is of such length that when the key member is in place the upwardly directed end portions 36^a thereof fit snugly against the vertical front and rear surfaces of the associated tooth 25^a of the stop bar whereas, the depending end portions 36^b fit snugly against front and rear edges of the retaining bar 33, thereby preventing any fore and aft horizontal movement of the retaining bar relative to the stop bar.

The lower surface of the retaining bar 33 is provided with a longitudinal engaging rib 37 extending continuously throughout its length and located preferably near or adjacent the front edge thereof, as shown in Figs. 7 and 8. The rib 37, which may be semi-circular in cross section, enters a correspondingly shaped depression or notch 38 in the upper edge of the yieldable detent portion 32 of each column stop 30 when such column stop is in its normal retracted or ineffective position. When the column stop is moved to its projected position, the rib 37 enters a second similar shaped depression or notch 39 also located in the upper edge of the yieldable portion 32 but spaced forwardly of the notch 38.

The length of the slot 34 and the closeness of this slot to the lower end of the column stop 30 are so proportioned that the yieldable detent portion 32 has sufficient resiliency to be cammed downwardly in changing the position of the column stop and yet such detent portion 32 should have sufficient stiffness to reliably hold the column stop in either its retracted or projected position against accidental displacement by jars, vibrations and the like. It will be noted in Figs. 7 and 8 that the slot 34 extends rearwardly beyond the upper slot 31 and that the rib 37 is located near the front of the retaining bar 33, thus increasing the length through which the yieldable detent portion 32 may be flexed during movement of the column stop.

The front end of the yieldable detent portion 32 of each of the column stops adjacent the stop lug 35 is sloped or provided with a cam edge 35^a to enable the column stops to be readily forced into position and assembled on the stop bar 25 and retaining bar 33 by forcefully sliding the column stops forwardly so that this sloping end of the

yieldable portion 32 is cammed below the retaining bar 33 and its rib 37. On the other hand, the column stops might be removed from the stop and retaining bars by prying or forcing down the free end of arm 32 of each stop so that the stop lug 35 thereon will clear the retaining bar 33. However, in assembling the complete column stop mechanism before mounting on the machine, it will be clear that the column stops 30 and key members 36 may be assembled on the stop bar 25 and the retaining bar 33 may then be inserted longitudinally through all the slots 34 of the column stops and through the spaces between the depending arms 36^b of the key member 36.

From a consideration of Figs. 2 and 5, it will be understood that the end portions 26^a of the bracket arms 26 extend across the ends of the retaining bar 33 when the latter is in place and limit or prevent any material longitudinal displacement of said bar 33 relatively to the column stop bar.

It also will be understood that when the parts are assembled the retaining bar 33 not only acts in that capacity in its cooperation with the detents on column stops, but also by its interlocking connection with the stop bar 25 through the stops 30, constitutes a reinforcing member which gives greater rigidity and strength to and prevents a flexing of the stop bar.

It will be seen, moreover, that there is but little machining of the parts required and that they may be produced and assembled at comparatively little expense.

The shape or profile of the present column stops 30 or particularly that of the upper and rear portions is intended to conform or substantially conform with that of column stops ordinarily employed in Remington machines. The rear vertical edge of these column stops 30 is beveled at 30^a in the usual manner. However, in the present construction the stops are devoid of separate springs each attached to a side of its stop by a rivet. In the present construction, each spring detent member 32 is integral with its stop and is located in the plane of the body portion thereof.

It will be apparent from the foregoing description that I have provided by the present invention a simple and inexpensive, yet highly efficient and reliable column stop assembly which may be readily incorporated in existing typewriting, accounting and like machines without modifying, or materially modifying the existing structural features of such machines. The column stops 30 of this assembly are possessed of great strength and rigidity and so designed that they may be effectively held in either their projected or retracted position, and yet each of such column stops and its spring detent may be fabricated from a single piece of sheet metal by a very inexpensive process of punching.

Various changes may be made in the construction, and certain features thereof may be employed without others without departing from my invention as it is defined in the accompanying claims.

What I claim as new and desire to secure by Letters Patent is:

1. In a typewriting or like machine, the combination of a toothed column stop bar, column stops mounted to slide in the interdental spaces in said stop bar into and out of effective position, a second bar detached from said column stop bar, and interlocking connecting means on said stops 75

for wholly supporting one bar by the other through said stops.

2. In a typewriting or like machine, the combination of a toothed column stop bar, column stops mounted to slide in the interdental spaces in said stop bar into and out of effective position, a second bar detached from said column stop bar, interlocking connecting means on said stops for wholly supporting one bar by the other through said stops, and detachable key members forming an interlocking connection between said bars and preventing a lateral relative displacement only between them.

3. In a typewriting or like machine, the combination of a toothed column stop bar, column stops mounted to slide in the interdental spaces in said stop bar into and out of effective position, a second bar distinct from said column stop bar, interlocking connecting means on said stops for supporting one bar by the other through said stops, and detachable key members forming an interlocking connection between said bars and preventing a lateral relative displacement between them, each of said key members having a 25 T-shaped head at opposite ends thereof which engages both bars when the key members are in place.

4. In a typewriting or like machine, the combination of a column stop bar having teeth projecting from opposite sides thereof, column stops each bifurcated to straddle said stop bar and slide thereon in aligned interdental spaces therein to and from effective position, each of said stops also having an integral spring detent, and a retaining bar with which said detents coact and which is received between said detents and one of the arms of the bifurcated portion of each stop.

5. In a typewriting or like machine, the combination of a column stop bar having teeth projecting from opposite sides thereof, column stops each bifurcated to straddle said stop bar and slide thereon in aligned interdental spaces therein to and from effective position, each of said stops also having an integral spring detent, a retaining bar with which said detents coact and which is received between said detents and one of the arms of the bifurcated portion of each stop, and detachable key members forming an interlocking connection between said bars to prevent a lateral relative displacement between them.

6. In a typewriting or like machine, the combination of a toothed stop bar, column stops having a first bifurcated portion slidable in the interdental spaces of said stop bar into and out of an operative position, a retaining bar, key means interspaced between certain of said column stops for holding said retaining bar against lateral displacement relatively to said stop bar, and a second bifurcated portion of said column stops straddling 55 said retaining bar and supporting it in place, and coacting means on said detent bar and on said second bifurcated portion of said column stops for holding said column stops against accidental displacement from either the inoperative or 60 operative position.

7. In a typewriting or like machine, the combination of a toothed stop bar, column stops having a first bifurcated portion slidable in the interdental spaces of said stop bar into and out of an effective position, a ribbed retaining bar, key means interspaced between certain of said column stops for maintaining said retaining bar spaced apart from said stop bar and for preventing relative lateral movement between them, and a second bifurcated portion integral with said first

bifurcated portion of said column stops straddling said retaining bar, and means on said second bifurcated portion of said column stops coacting with said ribbed retaining bar for holding said column stops against accidental displacement from either effective or ineffective position.

8. In a typewriting or like machine, the combination of a toothed stop bar, column stops each having a first bifurcated portion slidable in the interdental spaces of said stop bar to retracted or projected positions, a retaining bar, detachable key members interspaced between certain of said column stops for maintaining said retaining bar spaced apart from said stop bar and for preventing relative lateral movement between them, and a second bifurcated portion of said column stops straddling said retaining bar, and coacting means on said retaining bar and on said second bifurcated portion of each of said column stops for holding said column stops against accidental displacement from either said retracted or projected positions and for preventing accidental removal of the column stops from said stop bar.

9. In a typewriting or like machine, the combination of a column stop bar having transverse slots, sheet metal column stops, a first bifurcated portion on said column stops received in the transverse slots of said stop bar for movement in said slots into a projected or a retracted position on said bar, a retaining bar having a longitudinal rib, key members interspaced between certain of said column stops for retaining said retaining bar against transverse movement relative to said stop bar when said detent bar is placed in spaced parallel relation to said stop bar, a second yieldable bifurcated portion on each of said column stops embracing said retaining bar, and notches in said second bifurcated portion of each of said column stops coacting with the rib of said retaining bar to hold 40 said column stops against accidental displacement from either said projected or retracted position.

10. In a typewriting or like machine, the combination of a column stop bar having transverse slots, sheet metal column stops, a bifurcated portion on each of said column stops received in the transverse slots of said stop bar for movement in said slots into a projected or a retracted position on said stop bar, a retaining bar having a longitudinal rib, key members interspaced between certain of said column stops for holding said retaining bar against transverse movement relative to said stop bar when said retaining bar is placed in spaced parallel relation to said stop bar, a yieldable portion on each of said column stops embracing said retaining bar and having notches therein coacting with said rib of the retaining bar to hold said column stops against accidental displacement from either said projected or retracted position, and means on the yielding portion of each column stop coacting with said retaining bar to prevent removal of the column stops from the stop bar.

11. In a typewriting machine, the combination of a column stop bar, a series of column stops slidable to effective and ineffective positions on said stop bar, a retaining bar mounted in spaced parallel relation to said column stop bar, and yieldable means integral with each of said column stops and partially surrounding said retaining bar for supporting it in place and for holding each of said stops against accidental displacement from either said effective or ineffective position.

12. In a tabulating mechanism for typewriting and like machines, the combination of a plurality of stops, a toothed bar for guiding movement of said stops to effective and ineffective positions, a retaining bar, integral detenting means on each of said stops coacting with said retaining bar for arresting each of said stops in either said effective or ineffective position, and detachable key members interlocking with said toothed and retaining bars but otherwise free therefrom and acting jointly with said integral means of the stops to hold said retaining bar in spaced parallel relation to said toothed bar and against lateral movement relatively thereto.

13. In a typewriting or like machine, the combination of a toothed stop bar, a series of stops each having a first bifurcated portion slidable in the interdental spaces of said stop bar to effective and ineffective positions, a retaining bar extending in spaced parallel relation to said stop bar, key members interspaced between certain of said stops for preventing movement of said retaining bar relative to the stop bar in the direction of movement of said stops on the stop bar, a second yieldable bifurcated portion integral with each of said stops embracing said retaining bar to support it through said stops on the stop bar, and interfitting detent means on said second bifurcated portion of each of said stops and on said retaining bar for arresting each of said stops in either said effective or ineffective position.

14. In a typewriting or like machine, the combination of a toothed stop bar, a series of stops each having a first bifurcated portion slidable in the interdental spaces of said stop bar to effective and ineffective positions, a retaining bar extending in spaced parallel relation to said stop bar, key members interspaced between certain of said stops for preventing movement of said retaining bar relative to said stop bar in the direction of movement of said stops on the stop bar, a second bifurcated portion integral with each of said stops and having a yieldable member with means inter-engaging with the retaining bar for releasably holding each of said stops against accidental displacement from either said effective or ineffective position.

15. In a tabulator stop mechanism for typewriting and like machines having a transversely slotted stop bar, the combination of a retaining bar extending in parallel relation to said stop bar, and a series of flat sheet metal stops each having a slot therein that enables the stop to straddle the stop bar and to slide in slots in said stop bar to projected or retracted position, each stop also having a second slot therein forming a yieldable portion coacting with said retaining bar to releasably hold each of said stops in a projected or retracted position on said stop bar.

ELBERT S. DODGE. 30
